UNITED STATES PATENT OFFICE

GEORGE R. WILDERN, OF DETROIT, MICHIGAN

VALVE

Application filed October 17, 1927. Serial No. 226,535.

This invention relates to valves and particularly to a type designed for controlling the flow of gas to heaters, furnaces or the like, the principal object being to provide a new and novel construction simple in design and efficient in operation.

Another object is to provide a valve for controlling the flow of gas to a furnace or the like, in which a mass of mercury is employed as the sealing means.

A further object is to provide a thermostatically or otherwise automatically controlled valve for heaters or the like devices comprising a chamber into which said gas is introduced under pressure, said chamber being provided with a downwardly extending tube open at its lower end for the escape of gas from the chamber, a vertically movable cup being positioned below the open end of the tube and being filled with a heavy fluid such as mercury, the cup being actuated by a thermostatic or other automatic means, the construction of the device being such as to produce an accelerated opening or closing of the open end of the tube by the mass of heavy fluid in the cup.

The above being among the objects of the present invention, the same consists in certain features of construction and combinations of parts to be hereinafter described with reference to the accompanying drawing, and then claimed, having the above and other objects in view.

In the accompanying drawing which illustrates a suitable embodiment of the present invention, and in which like numerals refer to like parts throughout the several different views,—

Fig. 1 is a fragmentary partially sectioned back view of my device.

Fig. 2 is a sectional view taken on the line 2—2 of Fig. 1.

Fig. 3 is a fragmentary view illustrating a relative position of parts when the valve is closed against passage of the gas.

Fig. 4 is a fragmentary sectional view of a modified method of operating my valve.

The valve comprising the present invention is shown in the drawing as comprising 50 a pan-shaped casing comprising side walls

10, top wall 11, bottom wall 12 and back wall 13, the front face of the same being open. Intermediate the top wall 11 and bottom wall 12 is a cross wall 14 preferably positioned near the bottom wall 12. The side walls 10 and top and bottom walls 11 and 12 are provided with an outwardly extending marginal attaching flange 15 to which the cover plate 16 is secured by screws such as 17 and nuts 18, thus closing the casing and forming two separate chambers 19 and 20 therein. An opening 21 extends through one of the side walls 10 into the chamber 19 and is screw threaded for connection to a suitable source of gas under pressure. A boss portion 22 is formed on the opposite side wall 10 and is provided with a vertical opening 23 which is plugged at its upper end by the plug 24 and rigidly receives at its lower end the tube 25 which extends downwardly therefrom in a vertical direction and terminates at a point spaced above the upper surface of the interior wall 14. A cross opening 26 connects the opening 23 with the exterior of the casing and is threaded for connection to a pipe extending 70 to a burner or other gas consuming device in connection with which the device is employed; it being understood, of course, that the pipe may be connected directly to the opening 23 and the opening 26 eliminated if 75 desired, the latter opening being provided primarily to balance up the appearance of the device.

In axial alignment with the tube 25 in the wall 14 is an opening 27, and another opening 28 is provided in the bottom wall 12 in alignment with the opening 27 and tube 25, the bottom wall 12 being provided with a boss 29 at this point and the opening 28 being closed by a plug 30 at the lower end thereof. Slidably received in the openings 27 and 28 and projecting a short distance into the chamber 19 is a rod or shaft 31 to the upper end of which is secured a thin metal cup 32 the upper edge of which overlaps the lower edge of the tube 25 but is relatively widely spaced therefrom. Adjustably secured to the back wall 13 within the chamber 20 is a screw or anchor member 33, a nut 34 being provided for locking the same in its adjusted rotary position. A con-

ventional spiral coil 35 formed of thermo-static material has one end thereof received within the slot 36 of the screw member 33 to lock the same against movement, and the 5 outer extremity of the coil 35 is formed into an eye 37 through which a pin 38 passes and is threaded into the rod or shaft 31. A slot such as 39 may be provided in the lower end of the shaft 31 in order to prevent any suction or 10 pressure between the lower end of the shaft 31 and the plug 30 from interfering with the free vertical movement of the shaft 31. Within the cup 32 is a heavy liquid 40 such as 15 mercury.

15 The operation of the device will be apparent from the foregoing. The device is placed in a position to be affected by the temperature of a device or parts whose temperature is desired to be controlled, such as for instance 20 the water heater tank employed in homes or other places, in which case a suitable pipe (not shown) is connected from the opening 26 to the burner of the heater. The rotary position of the screw 33 and the level of the 25 liquid 40 within the cup 32 are so adjusted that when the water in the tank reaches a pre-determined temperature value the coil 35 will have expanded sufficiently to bring the surface of the liquid 40 sufficiently near the lower edge of the tube 25 to restrict the flow of 30 gas from the opening 21 up through the tube 25 and out through the opening 26 to the burner. The construction is such that as soon as the cup 32 is thus raised sufficiently to 35 restrict the flow of gas into the tube 25, the cup 32 will be accelerated in its upward movement and will have a "snap" to its movement whereby to immerse a substantial amount of the end of the tube in the liquid 40 and thus 40 effectively seal the tube 25 against the passage of gas, and on opening movement of the cup 32 unsealing the tube 25 a similar accelerated action will take place whereby to quickly open the tube 25 to the passage of gas. 45 This action is the result of the following:— The weight of the mercury or other heavy liquid 40 acts in opposition to the expanding force of the coil 35 and as soon as the surface of the liquid has been raised sufficiently to 50 restrict the flow of gas to the tube 25, the pressure of the gas within the tube 25 is lowered and the pressure of the gas within the chamber 19 acting on the surface of the liquid 40 in the cup 32 around the outside of the tube 25 55 forces some of the liquid 40 up into the casing, thus tending to relieve the coil 35 of supporting a portion of the weight of the liquid 40, and at the same time the pressure of the gas acting on the bottom of the cup over the cross 60 sectional area of the tube 25 also tends to raise the cup 32. These two features acting in conjunction at the time that the full flow of gas through the tube 25 is interrupted, acts to give the cup 32 a sudden upward movement which 65 has the effect of deeply immersing the tube

25 in the liquid 40 and sealing the same with a quick action, thereby preventing a continuance of the flow of gas under the edge of the tube as occurs in constructions that have been suggested in which the contact between the tube and the mercury is brought about gradually and which results in a spluttering of the liquid 40 and consequent loss of the same due to particles being carried out through the discharge tube. The position of the cup 32 with respect to the tube 25 and the action of the liquid 40 when the latter has moved to seal the end of the tube 25 is clearly 70 illustrated in Fig. 3.

75 It is a frequent occurrence to have particles of dust or other foreign matter carried by the gas and where such is the fact such dust is, of course, carried into the chamber 19 and a certain amount of the same is carried out through the tube 25. When this dust collects on the 80 surface of the mercury 40 it forms a scum or skin on the same which is relatively hard to break, and where the end of the tube 25 is left flat this scum may often exert sufficient 85 resistance to breaking by the tube 25 that gas will be forced downwardly between the tube and the mercury and carried upwardly into the tube between the walls of the same and the mercury, thus preventing an effectual seal 90 to the flow of gas. In order to prevent such leakage I bevel the end of the tube 25 so that the lower edge of the same presents a knife or cutting edge which readily cuts the dust skin 95 on the mercury and allows the mercury to contact directly with the tube 25, thus insuring a 100 complete seal against the flow of gas into the tube 25 when the device is in closed position.

105 When the tank or other device upon which the valve mechanism is secured to control its conventional manner, this tending to lower the cup 32 against the pressure of the gas. As soon as the coil 35 has cooled sufficiently 110 to exert a tension greater than the pressure of the gas acting on the bottom of the cup 32 as previously described, the cup 32 will move downwardly with the shaft 31 sufficiently to break the seal of the liquid 40, in which case the gas will rush into the tube. This not only 115 returns the original weight of the liquid 40 on the coil 35 but also relieves the action of the gas on the bottom of the cup 32, the gas pressure on the cup 32 thereafter being balanced. This action relieves the upward tension 120 on the coil 35 with a result that it suddenly contracts and lowers the cup 32 sufficiently to bring the level of the liquid 40 a sufficient distance below the tube 25 to completely open the tube 25 to the flow of gas. This action gives a quick opening and closing 125 valve which is essential to the success of an apparatus of this type employing a liquid for sealing the flow of gas under pressure and without which the practicability of the device is destroyed, due to loss of the sealing liq- 130

uid as described in the preceding paragraph.

The wall 14 not only provides a guide for the shaft 31 but also prevents the temperature of the gas entering the opening 21 from effecting the temperature of the coil 35.

In Fig. 4, I show a modified method of operating my valve. In this construction I provide no lower chamber 20 as in the construction above, but instead I secure to the lower wall 14 of the chamber 19 a valve casting 41 provided with an attaching flange 42 which is secured to the wall 14 by screw 43 or other suitable means. The casting 41 is provided with an inlet passage 44 and an outlet passage 45. The passage 44 is adapted to be connected to a source of water under pressure and the passage 45 is adapted to be connected to the gas heater to which the flow of gas is controlled by my mercury valve, and the water outlet side of the gas heater is connected to the various hot water faucets in the residence or other building in which the device is used. The passages 44 and 45 are connected by a restricted passage 46 and an enlarged circular opening 47. Slidably received in the opening 47 is a piston 48 having a rod 49 which projects upwardly therefrom through the upper wall of the casting 41 where it is sealed against leakage in a conventional manner, and thence slidably projects up through the wall 14. Within the chamber 19 a U-shaped spring member 50 is rigidly secured at one end to the upper end of the rod 49, and the cup 32 is rigidly secured to the opposite end of the spring member 50. A plug 51 closes the opening 52 in the lower face of the casting 41 and is provided to permit entrance of the piston 48 into the interior casting 41. A coil spring 53 is held under a predetermined tension between the plug 51 and the piston 48. A member 54, adjustably mounted on the shaft 49 by screw 55 limits the upward movement of the shaft 49 and, therefore, the upper position of the cup 32 in respect to the tube 25. The operation of this control is as follows:

If a faucet in the hot water line from the gas heater is opened the pressure in the passage 45 is reduced, and if such faucet is opened sufficiently to allow more water to flow out of the same than can flow through the passage 46 without a drop in pressure, a pressure difference is created between the passages 44 and 45 and this pressure difference acting on the piston 48 will move piston 48 downwardly. When the piston 48 moves downwardly the rod 49 follows its movement and tends to lower the cup 32. As soon as the force acting on the piston 48 is sufficient to overcome the gas pressure holding the cup 32 and the mercury therein in contact with the tube 25, the cup 32 moves downwardly and breaks the seal of the tube 25, thus allowing gas to flow through the tube 25 to the heater. When the faucet is shut off the pres-

sure in the passage 44 and 45 will, of course, equalize due to the flowage through the passage 46, thus balancing the water pressure on the piston 48 and allowing the spring 53 to move the piston 48 and rod 49 upwardly with the result that the mercury in the cup 32 is again brought into a sealing contact with the tube 25 and cuts off the supply of gas to the heater.

By inserting the spring member 50 between the rod 49 and the cup 32 I am enabled to get the same snap in the movement of the cup 32 to seal the tube 25 and to break the seal of the same as in the construction previously described. It will be apparent that a spring such as 50 may be employed in the temperature controlled construction shown in Figs. 1 to 3 inclusive, where a thermostat is used that does not provide the range of spring movement that is present in the specific type of thermostat shown, and also that where a valve mechanism operated by gas or other pressure, or electricity is employed to actuate my valve mechanism, such a spring is highly desirable to provide the snap action of the sealing and unsealing movement of the cup 32.

It will be apparent from the foregoing that the device provides a simple and exceedingly effectual valve for controlling the flow of gas, and further provides an arrangement in which an accelerating movement is imparted to the mass of mercury in its sealing and unsealing movement which is essential to a valve of this type.

Moreover it is to be understood that I do not limit myself to the specific means for operating the valve disclosed but that any suitable means for actuating the same may be provided in conjunction with the valve, and this means may depend on variation of temperatures in operating the same, variations of fluid pressure, electrical or manual means.

Formal changes may be made in the specific embodiment of the invention described without departing from the spirit and substance of the broad invention the scope of which is commensurate with the appended claims.

What I claim is:

1. In a device of the type described, a chamber, means for introducing a fluid under pressure into said chamber, means for conducting said fluid from said chamber comprising a tube fixed at its upper end and open at its lower end, means for supporting a mass of mercury adjacent to the lower end of the tube, and means for raising or lowering the last mentioned means to close or open the tube to the flow of the fluid comprising a unitary resilient member adapted to actively yield to variations of pressure acting on the mercury during operation of said device.

2. In combination, a chamber, means for introducing a fluid under pressure into the

chamber, means for conducting the fluid from the chamber comprising a member provided with a downwardly opening portion, means for movably supporting a mass of mercury adjacent the downwardly opening portion, and thermostatic means for moving the supporting means whereby to bring the mercury into or out of contact with the downwardly opening portion to control the flow of the fluid through the downwardly opening means, the thermostatic means including a unitary member yieldable to the pressure of the fluid, whereby to accelerate the contacts.

3. In combination, a chamber, means for introducing a fluid under pressure into said chamber, means for conducting said fluid from said chamber comprising a tube fixed at its upper end and open at its lower end, means for supporting a mass of mercury adjacent to the lower end of said tube, and means for raising or lowering the last mentioned said raising and lowering means including a spring element.

4. In combination, a chamber, means for introducing gas under pressure into said chamber, means for conducting gas from said chamber comprising a tube immovably supported adjacent the upper end thereof and projecting vertically downwardly in said chamber, means for movably supporting a mass of mercury adjacent the lower end of said tube, and temperature responsive means for raising or lowering said supporting means to bring said mercury into or out of contact with said tube whereby to cut off or to permit the flow of said gas through said tube.

5. In combination, a chamber, means for introducing gas under pressure into said chamber, means for conducting gas from said chamber comprising a downwardly extending tube in said chamber terminating at a point above the bottom thereof, a cup surrounding the lower end of said tube and spaced therefrom, a mass of mercury in said cup, and temperature responsive means for raising and lowering said cup in response to variations of temperature whereby to immerse the lower end of said tube in said mercury or withdraw said mercury from contact with said tube.

6. A thermostatic valve for controlling the supply of gas to a gas consuming device comprising a chamber, means for introducing gas under pressure to said chamber, an outlet passage including a tube extending downwardly into said chamber and terminating at a point above the bottom thereof, a cup member positioned adjacent the bottom of said tube and freely spaced therefrom, and temperature responsive means supporting said cup, said cup being provided with a mass of mercury therein and adapted to be moved upwardly by said temperature responsive means to bring said mercury into contact with the lower edge of said tube at a predetermined

temperature whereby to cut off the flow of said gas through said tube, the act of cutting off said flow of gas acting to accelerate the movement of said cup whereby to relatively deeply immerse the end of said tube in mercury. 70

7. In combination, a chamber, means for introducing gas under pressure into said chamber, a downwardly extending outlet pipe in said chamber, a cup member positioned at the lower end of said outlet pipe and spaced therefrom, said cup being supported on a vertically movable shaft, thermostatic means for controlling the vertical position of said shaft, and a mass of heavy fluid in said cup co-operable with the end of said pipe upon movement of said cup for sealing said pipe against the flow of said gas. 80

8. In combination, a chamber, means for introducing gas under pressure into said chamber, means for allowing gas to escape from said chamber comprising a fixed tube open at its lower end, means for supporting a mass of mercury adjacent the bottom of said tube, temperature responsive means for actuating said supporting means to bring said mercury into or out of contact with said tube, and means for preventing the temperature of said gas in said chamber from materially affecting the temperature of said 90 temperature responsive means. 95

9. In combination, a casing provided with an intermediate wall, a cover closing said casing and separating the same into a pair of chambers, means for introducing gas under pressure into one of said chambers, means for allowing gas to escape from said chamber comprising a fixed vertically positioned tube open at its lower end, means for supporting a mass of mercury adjacent the bottom of said tube, and a temperature responsive element positioned in the other of said chambers for raising and lowering said mercury in respect to temperature variations of temperature responsive means whereby to bring it into or out of contact with the lower end of said tube. 100 105

10. In combination, a casing provided with an intermediate wall, a cover closing said casing and cooperating with said intermediate wall to form the interior of said casing into an upper and lower chamber, means for introducing gas under pressure into said upper chamber, means for permitting the escape of gas from said upper chamber comprising a downwardly extending fixed tube in said chamber, a cup surrounding the lower end of said tube and containing a mass of mercury, and a temperature responsive element in said lower chamber connected with said cup for raising or lowering said cup to bring said mercury into or out of contact with said tube in response to temperature variations in said lower chamber to close or open the lower end of said tube to the passage of said gas. 115 120 125 130

11. In combination, a casing provided with an intermediate wall, a cover closing said casing and forming the interior thereof into two chambers one above said intermediate wall and one below the same, means for introducing gas under pressure into the upper of said chambers, means for the escape of gas from said upper chamber comprising a downwardly extending tube fixedly supported at its upper end, a vertically slideable shaft guided in said intermediate wall and projecting into both of said chambers, a thermostatic element in the lower of said chambers for controlling the vertical position of said shaft, a cup supported at the upper end of said shaft in adjacent relationship with respect to the lower end of said tube, and a mass of mercury in said cup movable into and out of contact with the lower end of said tube upon vertical movement of said shaft to seal said tube against the passage of said gas or to open it to the passage of said gas.

12. In a device of the type described, a chamber having an inlet and an outlet, a mass of mercury, and solid spring means supporting said mercury in adjacent relationship in respect to said outlet, said mercury being adapted to control the flow of fluid between said inlet and said outlet.

13. In a device of the type described, a chamber having an inlet passage and a downwardly opening outlet passage, a mass of mercury, and torsion spring means supporting said mercury in adjacent relationship with respect to the open end of said outlet passage, said mercury adapted to be moved into and out of contact with said open end to control the flow of fluid through said chamber.
